Primary Examiner — Clare Ann Gannon*(74) Attorney, Agent, or Firm* — Kilpatrick Townsend & Stockton LLP(57) **CLAIM**

The ornamental design for a shoe, as shown and described.

DESCRIPTION

FIG. 1 is a front medial perspective view of an embodiment of a shoe.

FIG. 2 is a lateral side view of the shoe of FIG. 1.

FIG. 3 is a medial side view of the shoe of FIG. 1.

FIG. 4 is a front view of the shoe of FIG. 1; and,

FIG. 5 is a rear view of the shoe of FIG. 1.

The evenly broken lines and the reduced opacity areas show portions of the shoe which form no part of the claimed design. The dash-dot-dash lines define the boundaries of the claimed design that form no part of the claimed design.
